CARBON PAPER

William E. Clarke, Toronto, Ontario, Canada

Application September 6, 1932, Serial No. 631,902,
and in Canada July 15, 1932

1 Claim. (Cl. 282—28)

The invention relates to improvements in carbon paper as described in the present specification and shown in the accompanying drawing that forms a part of the same.

5 One object of the invention is to effect economy in time and labour in the taking of carbon copies of original work, or the spacing of work sheets, by the provision of means whereby any number of sheets of carbon paper, or spacing sheets, may 10 be removed simultaneously, and without the necessity of handling the work sheets individually.

A further object of the invention is the provision of means whereby in the process of interleaving the carbon sheets any misalignment of 15 the carbon or work sheets will be instantly apparent.

A still further object is to provide a sheet of carbon paper having an uncoated portion whereby the sheet may be handled without the hands 20 of the user coming into contact with the coated portion, thereby prolonging the life of the carbon paper as well as avoiding the soiling of the hands and the smudging of the work sheets.

In the drawing Figure 1 is a plan view of my 25 improved carbon sheet.

Figure 2 is a view illustrating the method of withdrawing a sheet of carbon paper from two work sheets between which it is shown in said view.

30 Figure 3 is a plan view of one end of a carbon sheet showing a modified construction.

Like numerals of reference indicate corresponding parts in the various figures.

In the usual method of manufacturing carbon 35 paper the paper is passed over a roller operating in a vat containing the material with which the paper is to be treated and this roller is wiped by spaced mechanical means to provide a coated body on the sheet of paper of a width corresponding to the length of two sheets of carbon paper 40 when the original sheet is cut centrally, the portions left uncoated at each side of said body constituting marginal pieces, of which there will be one at one end of each sheet after the paper 45 has been cut into sheets. Heretofore it has been the custom upon the completion of the coating process to trim off this marginal piece but in the present invention such marginal piece, indicated by the numeral 1, is left integral with the body 2 and provides a tab which is adapted to project 50 beyond the work sheet whereby the sheet of carbon paper may be grasped for interleaving, or withdrawal from the work sheets, without the necessity of touching the coated body of the

It is of course understood that while this uncoated marginal piece is described hereinbefore as being at one end of the completed sheet of carbon paper it may lie at either side of said sheet if such a method of manufacture be employed as to render this practical. 60

The body of the carbon, or interleaving, sheet is cut away substantially opposite to the uncoated edge 1, as indicated by the numeral 3, so as to leave the registering portions of the work sheets 65 unspaced whereby when such portions of the work sheets are grasped the carbon, or interleaving, sheets may be withdrawn by simply pulling on the uncoated projecting marginal piece 1. 70

The carbon sheet is provided with one, or more, 75 sight openings, or windows, so that in the process of interleaving the sheets any misalignment of said sheets will be instantly apparent through said openings and can be corrected. In Figures 1 and 2 of the drawing this aligning means comprises a single opening 4 through the sheet, partially within the body of same and partially within the marginal piece, while in Figure 3 the opposite edges of the sheet are cut away, as at 5, to permit of aligning the work sheets, but it is of 80 course apparent that any desired number of such openings may be employed and that same may be positioned where desired. 85

In the operation of the invention the carbon, or spacing, sheets are placed between the work 90 sheets in the ordinary way and proper alignment determined by means of the opening, or openings, 4, or 5, and the whole then placed in a typewriter, or other machine. Upon the completion of the work the carbon sheets are removed simultaneously by simply grasping the work sheets with one hand at the point where the carbon sheets are cut away and pulling on the marginal piece, or pieces, of the carbon sheets with the other hand. 95

What I claim is:—

A reproducing sheet designed to be interposed between two work sheets, said reproducing sheet having a portion cut away from its reproducing area adjacent to the top end thereof, the reproducing sheet having a plain margin extension 100 adapted to project beyond the edges of the work sheets, said reproducing sheet being formed within its margin with an opening including a part at least of the plain margin to thereby expose a portion of the edges of each of the underlying 105 work sheets which would otherwise be covered by the reproducing sheet, whereby to determine the alignment of the edges of the work sheets by their exposure through said opening.

WILLIAM E. CLARKE. 110
